(57) **CLAIM**

The ornamental design for radio frequency identification tag, as shown and described.

DESCRIPTION

FIG. 1 is a front view of a radio frequency identification tag; FIG. 2 is a left side view of the radio frequency identification tag shown in FIG. 1;

FIG. 3 is a right side view of the radio frequency identification tag shown in FIG. 1;

FIG. 4 is a top view of the radio frequency identification tag shown in FIG. 1;

FIG. 5 is a rear view of the radio frequency identification tag shown in FIG. 1; and,

FIG. 6 is a bottom view of the radio frequency identification tag shown in FIG. 1.

The cross hatch shading shown in the drawings is understood to represent fabric and is understood to repeat uniformly throughout the areas on which it is applied. The dashed lines shown around the central elliptical area are understood to represent stitching.
